(57) **CLAIM**

The ornamental design for an insulin pump holster, as shown and described.

DESCRIPTION

FIG. 1 is a top perspective view of an insulin pump holster showing my new design.

FIG. 2 is a bottom perspective view of the insulin pump holster of FIG. 1.

FIG. 3 is a top plan view of the insulin pump holster of FIG. 1.

FIG. 4 is a bottom plan view of the insulin pump holster of FIG. 1.

FIG. 5 is a right side elevation view of the insulin pump holster of FIG. 1.

FIG. 6 is a left side elevation view of the insulin pump holster of FIG. 1.

FIG. 7 is a front elevation view of the insulin pump holster of FIG. 1; and,

FIG. 8 is a rear elevation view of the insulin pump holster of FIG. 1.

The broken lines depict portions of the article that form no part of the claimed design.

1 Claim, 6 Drawing Sheets
